HENRY L. SCHWARTZ, CARL A. QUAST, AND LOUIS SPITZ, OF MILWAUKEE, WISCONSIN

DOOR SPRING

Application filed February 25, 1930. Serial No. 431,104.

This invention pertains to door springs, and has primarily for its object to provide a simple, inexpensive, and efficient device of this character, in which the spring action is 5 reduced to a minimum, thus effectively closing the door without excessive slamming.

A further object resides in the provision of a door spring which acts as a gradual check and positive stop to limit the outward movement of the door, thus preventing banging against the wall of the building with resultant damage to the door.

A further object resides in the provision of a device of the foregoing character, which 15 is adapted to normally lay parallel to the door within the confined width of the door casing so as not to interfere with the use of double doors hinged upon opposite sides of the casing.

20 Incidental to the foregoing, a more specific object resides in the provision of a pair of spring-urged arms pivotally connected to a door and casing, respectively, and having their floating ends connected by means of a 25 link.

A still further object resides in the provision of a pair of attaching brackets adapted to be secured to a door and casing, respectively, for either right or left operation, and 30 each having pivotally connected thereto, a spring-urged arm, the floating ends of said arms being connected by a link, whereby a gradual check and positive stop is provided for the opening movement of the door, thus 35 relieving excessive strain upon the parts and preventing the door from swinging outwardly against the wall, and also enabling the door to be releasably held in open position by forcing the arms slightly past center.

40 With the above and other objects in view, which will appear as the description proceeds, the invention resides in the novel construction, combination and arrangement of parts substantially as hereinafter described, 45 and more particularly defined by the appended claims, it being understood that such changes in the precise embodiment of the herein disclosed invention may be made as come within the scope of the claims.

50 In the accompanying drawings is illus-

trated one complete example of the physical embodiment of the present invention constructed according to the best mode so far devised for the practical application of the principles thereof.

55

In the drawings, Figure 1 is a fragmentary section of a door and casing with the present invention applied thereto, the same being taken looking upwardly at the top of the casing;

60

Figure 2 is a similar view illustrating a door in open position;

Figure 3 is a transverse section taken on the line 3—3 of Figure 1; and

Figure 4 is a detail section taken on the line 4—4 of Figure 1.

Referring now more particularly to the accompanying drawings, the numeral 1 designates a conventional casing to which is attached a swinging door 2 provided with a conventional hinge 3, the door being hung to swing outwardly with relation to the casing, as illustrated in Figure 2.

A pair of brackets 4 and 4' are secured to the casing and door, respectively, at a position outwardly from the hinge, and as best shown in Figure 3, each bracket is provided with wings extending at right angles to each other to permit attachment of the device to doors swinging in either direction, thus eliminating the necessity of providing two different structures of brackets.

75 In the arrangement illustrated, the vertical wing of the bracket 4' is secured to the door by the screws 5, while the horizontal wing 85 of the bracket 4 is secured to the top face of the door casing 1 by screws 6. Were the door to swing in the opposite direction, the method of attachment would simply be reversed, and the horizontal wing of the bracket 4' secured to the top of the casing 1, and the vertical wing of the bracket 4 secured to the inner face of the door.

90 Pivots secured to each of the brackets 4 and 4' is an arm 7 having pivotally secured thereto an offset finger 8 for attachment of one end of the contractile spring 9, the opposite end of each spring being secured to ears 10 projecting from the brackets 4 and 4'. The outer or floating ends of the arms 7 are con-

95

100

nected by pivotal links 11 which compensate for the different movement of the arms 7 with relation to their attaching brackets.

In attaching the present invention, the 5 brackets 4 and 4' are secured to the casing and door outwardly from the hinge 3, and the arms 7 extend away from the hinge substantially parallel to the door in their normal position, thus enabling the device to be 10 attached within the confined width of the door casing 1, which permits the use of double doors hinged upon the opposite sides of the casing as, for instance, where it is desired to augment the regular door with a storm 15 door.

In operation, as the door is swung outwardly, it will be obvious that the arms 7 will be caused to swing upon their pivots away from the spring anchoring ears 10, thus gradually 20 increasing tension upon the springs 9, which serve as a check to gradually retard opening movement of the door as it reaches the limits of its travel determined by alignment of the arms 7, as shown in Figure 2. It 25 will be readily seen that tension is equally distributed upon both springs and because of the relatively small movement between the arms 7 and the spring anchor ears 10, minimum action of the springs is required, thus avoiding 30 excessive tension upon the springs, which retards the movement of the door when the same is released and requires minimum effort for the opening operation.

When the door is swung open with relation 35 to the casing, it will be readily apparent that the springs 9 will be gradually extended, thus serving as a gradual check upon the outer movement of the door, and as the door reaches that position where the arms 7, through their 40 link connections 8, are aligned, a positive stop is afforded, which will prevent the door from slamming into an adjacent wall or obstruction with resultant damage.

In the event that it is desired to maintain 45 the door 2 in open position, the same is readily accomplished by forcing the arms 7 slightly past center, as indicated by dotted lines in Figure 2, after the door has reached the limit of its outward movement. In this 50 position of the arms 7, the springs 9 are so closely aligned with the pivotal centers of the arms 6 as to be ineffective, and thus the door will be releasably maintained in this position. To effect closing, it is merely necessary 55 to swing the door outwardly again, bringing the arm 7 into alignment, after which the springs 9 function in their normal manner to effect closing of the door.

Obviously, as the door is released, the 60 springs 9 will gradually contract to swing the arms 7 upon their brackets and return the door to closed position, and while this is accomplished by contraction of both springs, in some instances where the device is used 65 upon a light screen door, which requires less

spring tension to effect the closing, either one of the springs may be taken off and the closing operation effected by the remaining spring.

From the foregoing, it will be seen that a 70 very simple, inexpensive and efficient door spring has been provided which permits operation of the door with a minimum effort, and in addition retards the movement of the door to such an extent that it reduces to a minimum slamming and sudden stopping of the door, as well as serving to positively limit its outer movement to prevent banging 75 against a wall or adjacent obstacle.

Due to the fact that the members secured 80 to the door and the casing are identical in structure, one set of dies is sufficient to form both, thus materially reducing cost of manufacture.

Also, as heretofore explained, the device 85 may be attached to a door and casing to compensate for movement of the door in either direction relative to the casing, and because of the compactness of the device, and its method of attachment, the same can be employed 90 in confined spaces, such as between two doors hinged to the opposite sides of the casing.

We claim:

1. A device of the character described comprising a pair of angular brackets connected to a door and door casing respectively, an arm having its one end pivotally connected to the horizontal portion of each bracket, a link pivotally connecting the other ends of said arms, apertured ears carried by the other angle of said brackets, and coil springs having one end connected to the apertured ears and the other end connected to the arms adjacent their ends which are pivotally connected. 95

2. A device of the character described comprising a pair of brackets connected to a door and door casing respectively, an arm having one end pivotally connected to the normal horizontal portion of each bracket, a link connecting the other end of the arms, an apertured ear on the other angle of each bracket, an offset apertured finger carried by each arm adjacent the pivoted connection and coil 100 springs having one end connected to the apertured ears and the other end connected to the apertured fingers for normally urging said door toward a closed position. 105

In testimony that we claim the foregoing 110 we have hereunto set our hands at Milwaukee, in the county of Milwaukee and State of Wisconsin.
